United States Patent Office

Des. 200,358

Patented Feb. 16, 1965

200,358

JAR

Arnold I. Lorenzen, deceased, late of Toledo, Ohio, by Gertrude M. Lorenzen, executrix, Toledo, Ohio, assignor to Owens-Illinois Glass Company, Toledo, Ohio, a corporation of Ohio

Filed Apr. 15, 1964, Ser. No. 79,516

Term of patent 14 years

(Cl. D58—8)

FIG. 1

The characteristic features of this design reside in the configuration shown in full lines on the drawing.

What is claimed is:

The ornamental design for a jar, substantially as shown and described.
